UNITED STATES PATENT OFFICE.

WESLEY C. GAY, OF AUGUSTA, GEORGIA.

ROD OR WIRE PANEL FENCE.

1,275,900.

Specification of Letters Patent. Patented Aug. 13, 1918.

Application filed February 16, 1918. Serial No. 217,634.

To all whom it may concern:

Be it known that I, WESLEY C. GAY, a citizen of the United States, residing at Augusta, in the county of Richmond and State 5 of Georgia, have invented certain new and useful Improvements in Rod or Wire Panel Fences, of which the following is a specification.

This invention relates to rod or wire panel fences, more particularly, to those wire fences which are made up of unit portions embodying one or more sections or panels which may be folded one upon the other, or each panel may be detached from the 10 adjoining panel for shipment. As is the case with this construction, such fences are employed for a variety of purposes. They are used as regular division fences, or as side walls for animal, or poultry houses, and 15 combination barbed wire and hog fences operating to turn swine as well as cattle.

The object of this invention is to produce a rod or wire detachable or folding panel fence of the character stated, the parts and 20 details of which are of a certain special formation and arrangement, whereby it is believed a fence structure is made unusually cheap and strong and available for all farm, 25 dairy, garden and poultry-growing purposes.

To illustrate the construction and arrangement of the parts of this invention the accompanying drawings are provided. Of the drawings, Figure 1 represents a side 30 view of one unit fashioned and erected in accordance with this invention. Fig. 2 is a plan view of one of the crosspieces having eyes at its ends. Fig. 3 is a side view of a hen house or pen for small stock, the construction of the wall shown being made in 35 accordance with this invention. Fig. 4 is a plan view of one of the cross-pieces which may have a single eye at one end and a double or tandem eye at the other end. Fig. 40 5 shows a frame of crossed wires or rods covered with fabric. Fig. 6 is a plan view of the end portion of one of the wires or rods of the frame mentioned, showing the eye at the end. Fig. 7 is a side view of one 45 50 of the wires or rods of the frame showing the hooks at the ends. Fig. 8 shows an arrangement of this invention wherein the posts are set in the ground slantingly and diverge upwardly. Fig. 9 is a side view of 55 this invention showing a modified construc-

tion for use as a barbed wire cattle fence as regards its upper portion, which is removable, and a hog fence constituting its lower part.

Throughout the drawings and this description the same number is employed to refer to the same part.

Considering the drawings, Fig. 1 shows a post driven into the ground, and an open-work wire or rod panel having crosspieces 2 provided at the ends with eyes 3 and 4. The eye 3 engages the post. The panels are completed by the vertical rods or wires 5, and the crosspieces and vertical pieces are welded together where they cross each other. 70 It is not intended, however, to limit this invention to panels wherein the rods or wires are united by welding at their junctions, as any known manner of firmly connecting the wires may be adopted. Pins 6 and 7 passed through the post 1 below the upper crosspiece 2 and above the lower crosspiece, restrain the panel from displacement upwardly or downwardly.

Adjoining the panel just above described, 80 and which in this explanation is termed the first panel, is the intermediate panel. It comprises the crosspieces such as the crosspiece 8, having hooks 9 and 10 at the ends, and it is shown that the hook 9 engages the 85 end eye 4 of the crosspiece 2 of the first panel. The end hooks of the other crosspieces of the intermediate panel engage the eyes of the crosspieces of the first panel corresponding to the eye 4 of crosspiece 2. The 90 vertical rods or wires 11 complete the intermediate panel, and the rods are welded at their crossings as previously explained.

At the right hand is shown the third panel having the crosspieces such as the crosspiece 12, provided with the eyes 13 and 14 at the ends. The eye 13 engages the hook 10 of the crosspiece of the intermediate panel, and the eye 14 engages the post 15. The other crosspieces of the third and intermediate panel are correspondingly engaged. The vertical rods or wires such as the wire 16 complete the third panel. It will now be understood that what may be called a unit 100 of fence construction made in accordance with this invention comprises three panels which may be termed the first, third and intermediate panels.

Considering Fig. 2, which represents a hen house or the like, it will be noted that 110

the posts 17 and 18 engage the end eyes of the crosspieces such as the eyes 19 and 20 of the crosspiece 21. This cross piece has a single eye at either end, and the construction is a modification of that shown in Fig. 1 to the extent set forth hereinafter, with respect to the first panel. The intermediate panel has also a crosspiece 22 at the top with the single eyes 23 and 24 at the ends. The eye 23 engages the post 18. The next lower crosspiece 25 of the intermediate panel shown in Fig. 2, is provided at the ends with the hooks 26 and 27. Here, it will be observed, that the first panel shown in Fig. 15 2 has a crosspiece 28, second from the top, and this crosspiece is provided with a single eye 29 at one end engaging the post 17, and double eyes at the other end. Of the double or plural end eyes of the crosspiece 28, the eye at the end is marked 30, and the eye or loop next thereto is marked 31. The hook 26 engages the eye 30, and the eye 31 engages the post 18. Vertical rods or wires 32 complete the first panel shown in Fig. 2, 25 and the crosspieces and vertical wires are welded at their crossings as before stated. The first panel is usually provided with a door 33. At the right of the intermediate panel is the post 34, and next on the right 30 is the third panel 35, having the double eyes 36 and 37, and the single end eye 38. The eye 36 engages the hook 27 of the crosspiece 25 of the intermediate panel, and the second eye 37 engages the post 34. The end or 35 single eye 38 engages the post 39.

The construction just described may be covered with a corrugated metal roof 40, supported by pins 41 and 42 passed through the posts 17 and 39. The vertical rods or 40 wires 43 complete the intermediate panel, and the rods or wires 44 belong to the third panel. All crossings are welded. The crosspiece 35 and its plural eyes 36 and 37 and end eye 38, are best illustrated in Fig. 45 4. To support the panels slightly raised from the ground, the pins 45 and 46 are passed through the posts 18 and 34 respectively.

Fig. 5 illustrates a frame comprising the 50 vertical rods 47 terminating in the hooks 48, welded to horizontal crosspieces 49 having end eyes 50. These vertical and horizontal rods or wires are further illustrated in Figs. 6 and 7. The frame so constructed 55 is covered with a sheet of fabric 51, and the purpose of the frame and fabric covering is to produce an extra part, which by means of the hooks and eyes described may be connected with the panels to form a shelter from wind for poultry or stock. It will 60 be understood, of course, that the covered frame represented in Fig. 5 is one piece, and a number of like pieces are employed when it is proposed to cover the entire exterior of 65 a hen house or the like set forth in Fig. 2.

One mode of utilizing this invention is shown in Fig. 8. The posts 52 and 53 are driven slantingly into the ground, diverging upwardly, and they are placed at a suitable distance apart. The fence is held in such 70 slanting position on either side by means of the horizontal braces 54, 55 and 56, of different lengths, engaging the fences at different points. Any number of fence units may be employed, the purpose of the V- 75 shaped arrangement being to support tomato vines or the like planted between the outwardly inclined fences.

Fig. 9 illustrates a barbed wire cattle fence removably combined or associated with 80 a hog fence arranged below it. At the left is shown the post 57. The upper crosspiece 58 of the first panel shown in Fig. 9 has the end eye 59 engaging post 57, and an eye 60 at the other end. The crosspiece 58 85 is provided with the customary barbs 61. The vertical rods or wires which complete the first panel are marked 62, and they have at their lower ends the hooks 63. The hooks 63 removably engage the uppermost crosspiece 64 of the hog fence or lower portion 90 of the construction set forth in Fig. 9. The crosspiece 64 has the end eyes 65 and 66, and the first panel of the hog fence is completed by the vertical rod or wires 67, riveted to the cross-pieces. The eye 65 engages the post 57.

The upper portion of the intermediate panel shown in Fig. 9 has the crosspiece 68, provided with end hooks 69 and 70. The 100 hook 69 engages the end eye 60 of the crosspiece 58 of the first panel, and its fellows of the intermediate panel engage the corresponding eyes of the first panel. It will be understood that all junctions of horizontal 105 and vertical rods or wires are welded or otherwise firmly secured. The barbs on the crosspiece 58 are marked 71, and the vertical rods or wires of the intermediate panel are referred to by number 72. 110

The intermediate hog fence panel shown in Fig. 9 carries a topmost crosspiece 74, and it has the end hooks 75 and 76, being in fact of the same form as the other intermediate panel crosspieces. The hook 75 engages the 115 eye 66 of the crosspiece 64 of the first panel. The intermediate panel of the hog fence is completed by the rods or wires 77.

The upper crosspiece of the third panel of the cattle fence portion shown in Fig. 9 120 is marked 78, and has the eyes 79 and 80. The eye 79 engages the hook 70 of the crosspiece 68 of the intermediate panel. The crosspiece 78 has the barbs 81, and the eye 80 of the crosspiece engages the post 82. The third panel is completed by the vertical rods or wires such as the rod 83, and all the vertical rods are provided with hooks at their lower ends, such as the hook 84. Those hooks engage the upper crosspiece 85 of the 125 130

third panel of the hog fence portion shown in Fig. 9. This crosspiece has the end eyes 86 and 87. The eye 86 engages the hook 76 of the crosspiece 74 of the intermediate panel 5 of the hog fence, and the eye 87 engages the post 82. The third panel of the hog fence portion is completed by the vertical rods or wires 88.

As previously stated, the upper or cattle fence, the barbed portion, is removable from the hog fence or lower portion. The cattle fence is supported upon the posts 57 and 82 by the pins 89 and 90 passing through the posts. The hog fence portion is prevented 15 from being displaced upwardly by the pins 91 and 92 passing through the posts 57 and 82 just above the end eyes 65 and 87, as set forth in Fig. 9.

The operation of this invention is believed 20 to be clearly discernible from the foregoing description. If the posts are withdrawn from the ground, the three panels may be folded one upon another, or detached and placed one upon another for transportation. 25 In erecting the fence, by reason of the construction set forth, there is no part but which is light enough to be easily and quickly handled and adjusted, and that is true equally if the rods are relatively thick—say 30 one-fourth inch in diameter—where a strong fence is needed.

Having now explained this invention and

described its purpose and the manner of using it, what I claim is:—

1. In a fence of the character described, 35 the combination with posts, of first and third panels having cross-pieces provided with an eye at each end, each of the said cross-pieces having its said eye engaging a post, an intermediate panel having cross-pieces spaced 40 correspondingly with the said cross-pieces of the first and third panels, the said cross-pieces of the first and third panels having coupling devices projecting from one set of said eyes which engage the posts at the end 45 of the said cross-pieces, and the ends of the cross-pieces of the said intermediate panel being provided with means for engaging the said coupling devices.

2. In a fence of the character described, 50 the combination with posts, of first and third panels having crosspieces each provided with a single eye at one end and a double eye at the other end, each crosspiece having its said single eye engaging a post, 55 an intermediate panel having crosspieces provided with hooks at the ends engaging one of the said double eyes of the said crosspieces of the said first and third panels, and the remaining eyes of the said double eyes of 60 the crosspieces engaging certain of the said posts.

In testimony whereof I affix my signature.
WESLEY C. GAY.
